UNITED STATES PATENT OFFICE.

CHARLES W. PETITJEAN, OF UNION CITY, CONNECTICUT, ASSIGNOR TO THE BRISTOL COMPANY, OF WATERBURY, CONNECTICUT, A CORPORATION OF CONNECTICUT.

HUB CAP FOR CHARTS.

Application filed February 14, 1923. Serial No. 618,910.

To all whom it may concern:

Be it known that I, CHARLES W. PETITJEAN, a citizen of the United States, and a resident of Union City, in the county of New Haven and State of Connecticut, have invented certain new and useful Improvements in Hub Caps for Charts, of which the following is a specification.

The invention relates to a retaining member for use in holding a record chart of a recording gauge or the like on a rotatable arbor. Such holders usually embody a base or hub member fitting over the arbor and a removable cap portion for holding the chart to the hub; and the invention has for its object a compact device, thereby to reduce the combined height of the base and holding cap to a minimum for fitting within a closed casing; and, also, to provide a construction whereby the said cap portion may be readily positioned and more quickly drawn against the abutment for holding the chart therebetween, merely a partial turn of the cap being required. This is effected by an engagement between multiple threads, respectively provided on a shank of the base member and the inner surface of the cap.

The invention relates, furthermore, to a construction whereby the threads exposed for engagement are perfect to the limit of engagement. Moreover, the invention comprehends the provision of means whereby all of the multiple threads will be caused to go into action simultaneously without danger of the threads becoming crossed.

The nature of the invention, however, will best be understood when described in connection with the accompanying drawings, in which—

Fig. 1 is an elevation of the two parts composing the retaining member, the same being shown in separated condition.

Fig. 2 is a vertical section thru the retaining member with the respective parts in clamping position.

Similar characters of reference designate corresponding parts thruout the several views.

Referring now to the drawings, 10 designates a hollow hub serving as a base or abutment member for a chart 11, said base being adapted for use in connection with recording gages and the like and held thereto, for example, by a taper fit upon a rotatable arbor 12 of the gage (not shown). The

base member 10 is provided with a stem or shank having over its outer portion multiple threads 13. There is designed, moreover, to fit over the said shank a sleeve 14 provided with a flange 15 upon which the chart is to be supported and held, said sleeve having a forced fit thereon and shouldering against an enlargement 16 at the one end of the base. The sleeve 14, however, does not entirely cover the multiple threads, but a short portion at the outer end of the shank remains exposed; and in this manner perfect threads may be provided to the limit of engagement at the corresponding end of the sleeve. If the base or abutment member and sleeve were made integral, it would be practically impossible, from a mechanical standpoint, thus to insure perfect threads to the limit of engagement.

Moreover, to reduce the height of the base and cap members sufficiently so that the cover of the gage need not be an undue distance above the surface of the chart, multiple threads are required; and in employing such multiple threads for this purpose, difficulty would be experienced in starting a cap member 17 which is to hold the chart to the flange of the sleeve. To this end, the sleeve portion is somewhat elongated and designed to center the cap member which is accordingly made hollow and has a smooth cylindrical inner portion adapted accurately to fit over the said sleeve, and terminating in threads 18 at its outer end. By merely placing the cap over the sleeve, therefore, the former will thus be accurately centered without danger of crossing of the threads so that in rotating the cap to screw same on the base member each of the plurality of threads is simultaneously started in engagement and the cap may quickly be brought down to the flange in view of the multiplicity of threads, preferably four, a partial turn merely being necessary to positively and securely lock the chart 11 in place. Similarly, a partial turn in the reverse direction will serve to unlock the chart for removal.

In order conveniently to cut the threads 18 of the cap 17 in the manufacture of the holding member, the top is left open until the said threads have been cut in order to admit the proper tapping tool, whereupon a cover member 20 is placed over the opening and held to the top of the cap by swag-

ing over the edges of the cap. A hole 21 may be centrally provided therein to receive a chain 22 or the like by which the cap is secured to some fixed part (not shown) to prevent loss of the cap.

I claim:—

1. A chart retaining member, comprising: a base member having a multiple-threaded shank, a flanged sleeve fitting over the 10 threaded shank to expose an outer portion thereof only, the exposed threads remaining perfect to the outer end of the sleeve, a hollow cap member having a flange to cooperate with the flange of the sleeve in holding a chart and having a smooth inner wall 15 portion to fit over the said sleeve, and threaded at the inner end for engagement with the multiple threads of the shank, the sleeve centering the cap and guiding its 20 threaded portion to the threads of the shank so that all will start simultaneously as the cap is rotated.

2. A chart retaining member, comprising: a base member having a multiple-threaded 25 shank, a flanged sleeve fitting over the threaded shank to expose an outer portion thereof only, the exposed threads remaining perfect to the outer end of the sleeve, a hollow cap member having a flange to 30 operate with the flange of the sleeve in hold-

ing a chart and having a smooth inner wall portion to fit over the said sleeve, and threaded at the inner end for engagement with the multiple threads of the shank, the sleeve centering the cap and guiding its 35 threaded portion to the threads of the shank so that all will start simultaneously as the cap is rotated, and a cover member for the cap.

3. A chart retaining member, comprising: 40 a base member having a multiple-threaded shank, a flanged sleeve fitting over the threaded shank to expose an outer portion thereof only, the exposed threads remaining perfect to the outer end of the sleeve, a 45 hollow cap member having a flange to cooperate with the flange of the sleeve in holding a chart and having a smooth inner wall portion to fit over the said sleeve, and threaded at the inner end for engagement 50 with the multiple threads of the shank, the sleeve centering the cap and guiding its threaded portion to the threads of the shank so that all will start simultaneously as the cap is rotated, and a perforated cap and 55 securing means passing therethru.

Signed at Waterbury in the County of New Haven and State of Connecticut this 10th day of February A. D. 1923.

CHARLES W. PETITJEAN.
